UNITED STATES PATENT OFFICE.

IRA A. BURNETT, OF CHICAGO, ILLINOIS.

DENTAL AMALGAM OR ALLOY MIXER.

Application filed November 3, 1923. Serial No. 672,685.

To all whom it may concern:

Be it known that I, IRA A. BURNETT, a citizen of the United States, residing at Chicago, in the county of Cook and State of Illinois, have invented certain new and useful Improvements in Dental Amalgam or Alloy Mixers, of which the following is a specification.

This invention relates to improvements in agitating or mixing devices, and particularly to that type of such devices which are intended for use in connection with motor-driven dental-engine hand-pieces or other suitable rotatable shafts or spindles, by dentists, for thoroughly and quickly, mixing the ingredients of alloy or amalgam used for dental purposes, and it consists in certain peculiarities of the construction, novel arrangement and combination of the various parts thereof as will be hereinafter more fully set forth and specifically claimed.

The main object of the invention is, to furnish a mixer for the ingredients of amalgam, alloy and the like, which shall be simple and inexpensive in construction, attractive in appearance, strong, durable, efficient and noiseless in operation, with its parts so made and arranged that it can be held in one hand of the operator during its operation, or if desired, can be mounted on a table or other suitable support while being operated, and also, that it can be quickly applied to or removed from the chuck of the engine hand-piece, or other rotatable member, employed for imparting motion to the parts of the device.

Another and important object, is, the provision of means whereby the container for the ingredients to be mixed will be moved in such a way as to afford a rubbing action to said ingredients, in addition to the agitating or dashing movement thereto, thus effecting the mixture quicker and more thoroughly.

45 In the drawings,—

Fig. 1 is a face view in elevation of a mixer embodying the invention.

Fig. 2 is a vertical sectional view taken on line 2—2 of Fig. 1 looking in the direction indicated by the arrows, and

Fig. 3 is a plan sectional view taken on line 3—3 of Fig. 2 as indicated by the arrows.

Like numerals of reference refer to corresponding parts throughout the different views of the drawing.

The body or frame of the device comprises a base portion 5 having a flat bottom to rest on a table or stand if desired, and provided with an upwardly extended hollow and channeled portion 6 terminating at its upper end in a forwardly extended flange 7 which is horizontally disposed, as shown in Figs. 1 and 2 of the drawing. The channel 8 in the rear portion of the upright 6 is rectangular in shape, while the hollow or cavity 9 in the front portion of the part 6 is substantially circular when viewed from the rear, or in other words, the front portion of the upright part 6 is concavo-convex, as will be readily understood by reference to the drawing. The body or frame also includes a rear upright member 10 which is closely fitted between the side walls of the channel 8 in the upright 6 and rests at its lower end 75 on the bottom of said channel. The member 10 is of sufficient length to extend a considerable distance above the flange 7 of the upright portion 6 and is provided in its upper portion with an elongated cavity 11 over 80 which cavity is placed and secured to the front surface of the member 10 a plate 12 of metal or of any other suitable material, which plate is provided with a vertically disposed slot 13 in front of said cavity. 85

The plate 12 by preference is co-extensive with the member 10 and as shown lines the front surface of said member and has in its lower portion an opening 14 in which is located the front end of a sleeve or bushing 15, 90 which latter is extended through a rearwardly and horizontally extended hollow enlargement 16 on the lower portion of the member 10. Located in the sleeve 15 for rotation therein is a shaft 17 which has on its front end a disk 18 provided with an eccentric or wrist pin 19 located near its periphery. The rear portion of the shaft 17 is provided with a reduced screw-threaded portion 20 around which is mounted a washer 100 21 which rests against the rear ends of the sleeve 15 and the enlargement 16 and is held in such position by means of a nut 22 engaging the screw-threaded portion 20 rearwardly of said washer. Extended rearwardly from the portion 20 of the shaft 17 is a spindle 23 which can be inserted in the hand-piece 24 of a dental engine so as to be engaged by the chuck thereof when it is desired to operate the device. The projection 110 16, washer 21, and nut 22, are enclosed by a cup-shaped cap 25 which is secured at its

edges to the rear upper part of the base 5 and to the rear surface of the sides of the upright portion 6 as well as to the rear portion of the member 10 by means of screws or otherwise. This cap is provided centrally thereof with a hollow extension 26 which surrounds the spindle 23 and acts as a guide for the tapered front portion of the hand-piece 24 when the latter is being connected to the mixer for operating its parts.

Pivottally secured at its lower end to the wrist pin 19 is a pitman 27 which extends upwardly through the channel 8 in front of the plate 12 to a point near the upper end of said plate. At a suitable distance below its upper end the pitman 27 is connected to the plate 12 by means of a stud 28 which is extended through the slot 13 in said plate in such a way as to permit of its longitudinal movement in said slot. Mounted around the stud 28 between the pitman 27 and plate 12 is a washer 29 which holds the pitman in parallelism with the plate 12, it being understood that the front end of the stud 28 is provided with a head or enlargement to prevent displacement of the pitman. The rear end of the stud 28 is provided with a head 30 between which and the rear surface of the plate 12 a washer 31 is placed around the stud. The upper end of the pitman 27 is provided with a forwardly and downwardly extended spring 32 the lower end of which has mounted thereon an inverted cap 33 which has its lower front portion cut away as at 34, see Fig. 1, for the purpose of facilitating the insertion into said cap and removal therefrom of a container 35 for the ingredients to be mixed, which container is by preference in the form of a capsule of large size such as is commonly used for administering medicine.

At a suitable distance below the stud 28 the pitman 27 is provided with a forwardly extended bracket 36 which has on its upper portion a cup 37 to receive and retain the lower end of the container 35 for the ingredients to be mixed. The spring 32 on the upper end of the pitman 27 forms the major part of a circle and is preferably surrounded by a spiral coiled wire or spring 38 which will not only increase the tension of the spring 32 but will afford a better hold when the lower portion of the spring 32 is pressed upwardly against its tension in order to disengage the cap 33 from the upper end of the container so that it can be readily removed from the holder therefor comprising the cap 33 and the bracket held cup 37 on the front surface of the pitman.

From the foregoing and by reference to the drawing, it will be seen and readily understood that by fitting a hand-piece 24 of a dental engine on the spindle 23 so that said spindle will be engaged by the chuck

of said hand-piece, rotary movement may be imparted to the shaft 17 and disk 18, thereby causing the pitman to be reciprocated very rapidly, in which movement it is apparent that the ingredients within the container 35 will not only be dashed from one end of the container to its other end, but as the container will be caused to assume diagonally disposed or vertically inclined positions with respect to the guide slot 13 for the stud 28 of the pitman in each stroke of the latter, the ingredients will be rubbed against the opposite sides of the container, thereby causing a more thorough and much quicker mixture of the ingredients.

The parts 5, 6 and 10 constituting the body or frame of the device may be made of hard rubber, bakelite, or any other suitable material, and when the parts are assembled as shown, it is obvious that the device can be held in one hand of the user by placing it so that the part 6 and cap 25 may be grasped by the hand, thus leaving the other hand free for holding and manipulating the engine hand-piece.

Having thus fully described my invention, what I claim as new and desire to secure by Letters Patent is:

1. In a mixer of the class described, the combination with a body or supporting frame having a housing near one of its ends and a longitudinally extended slot terminating near its other end, of a shaft transversely journaled in said housing and having at one of its ends a spindle, a disk centrally mounted on the other end of said shaft and having an eccentric or wrist pin, a guide extension carried by said frame and surrounding said spindle, a pitman pivotally connected at one of its ends to said pin and extended in parallelism with said slot, means carried by the pitman and engaging said slot for longitudinal movement therein, a holder carried by the pitman comprising a bracket fixed thereon and a spring actuated cap supported by the pitman but spaced from said bracket, and a container interposed between said bracket and cap.

2. In a mixer of the class described, the combination with a body or supporting frame having a base portion provided with an upwardly extended hollow and channeled portion, of an elongated member fitted in said channel and having in its upper portion a longitudinally extended cavity, a longitudinally slotted plate secured to the surface of said member having the cavity therein, said member having at its lower portion a lateral extension provided with a transverse opening, a shaft journaled in said opening and having at one of its ends a spindle, a disk on the other end of said shaft provided with a wrist pin, means on said shaft co-operating with said extension for preventing its movement in one direc-

- tion, a cap surrounding said extension and secured to the body or frame and having a hollow extension surrounding said spindle, a pitman pivoted at one end on said wrist 5 pin and extended in parallelism with the slot of said plate, means carried by the pitman and engaging said slot for longitudinal movement therein, a holder carried by the pitman comprising a bracket fixed thereon 10 and a spring actuated cap supported by the pitman but spaced from said bracket, and a container interposed between said bracket and cap.
3. In a mixer of the class described, the 15 combination with a body or supporting frame having a housing near one of its ends and a longitudinally extended slot terminating at its outer end near the other end of
- said body, of a shaft transversely journaled in said housing and having at one of its 20 ends a spindle, a disk centrally mounted on the other end of said shaft and having an eccentric or wrist pin, a pitman pivotally connected at one of its ends to said pin and extended in parallelism with said slot, means 25 carried by the pitman and engaging said slot for longitudinal movement therein, a holder carried by the pitman comprising a bracket fixed thereon and a spring-actuated cap supported by the pitman but spaced 30 from said bracket, and a container interposed between said bracket and cap, said pitman carrying means for engagement with said slot being located about midway between the ends of said container.

IRA A. BURNETT.
